PULL TAPE FOR REMOVING CONTAINER COVERS

Roy Nasello, Brooklyn, N. Y.

Application July 25, 1955, Serial No. 524,085

1 Claim. (Cl. 229—43)

This invention relates to new and useful improvements in cartons or containers of the type used for drinks, ice cream, and other substances.

More particularly, the present invention proposes the construction of an improved container for potables and other substances which has a cap or lid slidably and frictionally secured to the body of the container with a pull tape means secured at one end to the container easily and quickly to remove the cap or lid.

As a further object, the present invention proposes securing one end of the tape to the body portion of the container at one side of the container and forming the container of two-ply material with the secured tape held between the two plies and extending from an upper rolled edge thereof and adapted to fit across the container and between the cap and the container with the free end of the tape disposed outside the container beneath and below the cap.

Still further, the present invention proposes securing the tape at one end to the center of the cap, the cap being provided with a central opening for the tape to extend through and across the inside of the cap between the cap and the body of the carton or container for disposal of the free end of the tape outside the container.

Another object of the present invention proposes forming the tape as a cord secured around the upper edge of the body of the container at one side thereof and having a pull tab secured to the other end of the cord for disposal outside the container beneath the cap.

A further object of the present invention proposes forming the container cap with two plies and securing one end of the tape to the cap at one side thereof between the two plies, the tape being adapted to extend across the inside of the cap and between the cap and the body of the container at the opposite side of the cap for disposal of the free end of the tape outside the container.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a perspective view of a container constructed and arranged in accordance with the present invention.

Fig. 2 is an enlarged sectional view taken on line 2—2 of Fig. 1.

Fig. 3 is a side view of the container shown in Figs. 1 and 2 with the cap partly removed.

Fig. 4 is a fragmentary perspective view illustrating a modification of the present invention.

Fig. 5 is a view similar to Fig. 1 but illustrating another modification of the present invention.

Fig. 6 is an enlarged fragmentary sectional view taken on line 6—6 of Fig. 5.

Fig. 7 is a perspective view of the inside of a cap illustrating another modification of the present invention.

2

Fig. 8 is a view similar to Fig. 6 but showing the cap of Fig. 7.

Fig. 9 is a view similar to Fig. 2 but illustrating still another form of the present invention.

5 The container, in accordance with the first form of the invention illustrated in Figs. 1 to 3, inclusive, is designated generally by the reference numeral 15.

10 Carton or container 15 may be made of any material, the most common material for such cartons being heavy waxed paper.

15 Container 15 has a body or body portion 16 and a cap or lid 17. The body portion 16 is cylindrical and hollow with an upper open end 18 and a closed lower end 19 having a bottom 20 therein.

10 Body portion 16 preferably is made of two plies spiraled in opposite directions and has a rolled upper edge 21 at the upper open end 18.

15 Cap 17 is of the same shape as the body 16 and is adapted slidably and removable to fit over the open end

20 18 of the body 16 and onto the body. The cap 17 is frictionally held to the body of the container by its sliding fit.

25 A tape or band 22 of thin flexible and relatively wide material has one end 23 secured to the container, this end 23 being disposed between the two plies 24 and 25 of the body 16 and secured, as by cement, thereto at one side of the body. The tape 22 may be made of plastic, fabric, paper or the like.

30 Tape 22 extends from the body 16 out the rolled edge 21 at one side of the body and is of a length sufficient for the tape flatly to extend across the upper end 18 of the body and between and beyond the cap 17 and the body 16 at the other side of the body when the cap is on the body of the container. The thin flat tape extends 35 between the outer side of the body and the inner side 26 of the lip or flange 27 of the cap 17. The free end 28 of the tape is disposed outside the body beneath the cap 17 and below the cap.

35 To remove the cap from the body when the tape is 40 extending across the upper end of the body as described, it is necessary only to pull upon the free end 28 of the tape 22. This easily and quickly pries off the lid or cap.

40 The modification of the present invention illustrated in Fig. 4 is characterized by the provision of a carton or 45 container 30 having a body 31 with a rolled upper edge 32. A cord opening 33 is provided in the body 31 adjacent the edge 32 at one side of the body. A tape or cord 34 extends through the cord opening 33 over and around the edge 32 and to the other end 35 of the cord 50 is secured a tab 36 disposed outside the container. To remove a lid or cap from the container all that is necessary is to pull up on the tab.

45 The modification of the invention illustrated in Figs. 5 and 6 is characterized by the provision of a cap 40 55 for a container body 41. The body 41 has the usual upper edge 42. Cap 40 has a central opening 43 through which extends a tape 44, one end of the tape being outside the cap 40 and disposed against the top 45 thereof and secured thereto as by a knot.

55 The tape 44 is a thin, flexible relatively wide band of a length to extend across the inside of the cap 40 and down the flange or lip 46 of the cap between the cap and the body 41 when the cap is on the body. The free end 47 of tape 44 is disposed outside the body 41 beneath the cap when the cap is in place.

60 The modification of the invention illustrated in Figs. 7 and 8 is characterized by the provision of a container 50 having a lid or cap 51 and a body 52. The cap 51 is made in two plies 53 and 54 and a tape 55 has one end 57 secured to the cap between the plies at one side of the cap. The tape is thin, flat and flexible and adapted

to extend across the inside of the cap and between the cap and the body at the opposite or other side of the cap. The free end 58 of the tape is disposed outside the container beneath the cap.

The modification of the invention illustrated in Fig. 9 is characterized by the provision of a container 69 having a lid or cap 61 and a body 62. The body 62 has an annular groove 63 adjacent but spaced from its upper lip 64 and the edge 65 of the lid or cap 61 fits in this groove. At one side of the body above the groove 63, a ribbon opening 66 is provided and one end of a ribbon 67 extends through this opening. The ribbon 67 also extends into the groove 63 between the groove and the edge 65 of the lid or cap 61 and extends across the container beneath the lid or cap 61. The ribbon 67 also extends up between the groove and the edge 65 of the lid or cap 61 at the other side of the container and over the lip 64 with a free end 68 of the ribbon disposed outside the container. Ribbon 67 may be a plastic tape or string or any other like material. It may be secured to the container adjacent the ribbon opening 66 or may be left free. The container 60 is conical.

While I have illustrated and described the preferred embodiments of my invention, it is to be understood that I do not limit myself to the precise constructions herein disclosed and that various changes and modifications may be made within the scope of the invention as defined in the appended claim.

Having thus described my invention, what I claim as new, and desire to secure by United States Letters Patent 30 is:

A container for potables and other substances comprising

ing a cylindrical hollow two-ply body with an upper open end and a closed lower end having a bottom therein, an upper edge at said upper open end of the body, a cap having a downwardly extending peripheral flange adapted slidably and removably to fit over said open end and overlap the body, and a flexible tape having one end secured to the body adjacent said edge, said tape being adapted to extend loosely across the open upper end and the upper edge of the body and between the flange of the cap and the body with a free end disposed outside the body and beneath and beyond the flange of the cap, said end of the tape being anchored between the plies of the body at one side and extending from the other side of the body.
